UNITED STATES PATENT OFFICE

2,437,694

METHOD FOR BLENDING POWDER GRAINS

Clarence N. Hickman, Jackson Heights, N. Y.,
assignor to United States of America, as represented by the Secretary of War

Application May 15, 1946, Serial No. 669,765

4 Claims. (Cl. 52—20)

(Granted under the act of March 3, 1883, as amended April 30, 1928; 370 O. G. 757)

1

The invention described herein may be manufactured and used by or for the Government for governmental purposes, without the payment to me of any royalty thereon.

This invention relates to the manufacture of service explosives, and more particularly to a new and improved method and apparatus for blending service smokeless powder utilized for rocket propellents.

The blending of powder lots is an important operation in powder manufacturing, without which uniformity in ballistic performance could not be obtained, because it is impossible to accurately control the chemical manufacturing processes so that each batch of powder will have exactly the same properties. A powder index or lot, as made up for service use, consists of 50,000 pounds or more of powder and in order to make up such a lot it is necessary to use dried grains from a number of different powder batches. The grains from the different powder batches must be thoroughly mixed or blended to give uniformity throughout the lot.

The blending of powder, as accomplished by the prior art, is carried out in blending towers. One type of blending tower consists of a series of bins arranged in horizontal groups, the groups being positioned in vertical relation to each other. The bins of each group may be in polygonal relation, each bin having a trap or gate valve facing toward the center of the group. In blending, the top group of the bins is charged with the required amount of powder from each of the selected batches. The trap or gate valves are opened simultaneously and the powder from all the bins falls to the next group in a single stream which divides about equally into the bins of the next group. This operation is continued from group to group and the powder is finally drawn off through a hopper at the bottom of the blending tower. In other blending towers the powder in the first blending bin is released to fall over a distribution cone before entering the next lower group of bins. This distribution cone improves the blending of the powder. If a high degree of uniformity is desired, however, it is necessary to run the powder through the blending tower a number of times. One characteristic disadvantage of this prior art blending process is the hazard involved due to the development of static electricity. Although apparatus has been designed to remove the electric charge from the parts of the system, the addition of this apparatus rather complicates the structure and is not entirely satisfactory.

2

In one type of rocket motor, as many as 30 individual grains, each about 5 inches in length and about $\frac{1}{8}$ inch in diameter, are used. Different loading performances have been found, traceable only to non-uniformity in the powder lot from which the loadings were made, i. e., to inadequate blending of the powder. Because of the tremendous hazards involved, it has not been possible to blend powders of this larger grain size with the mechanical means known to the prior art, hence, it is an object of this invention to provide a method and apparatus for blending powders of $\frac{1}{8}$ inch grain size or larger which is non-hazardous and which produces a higher degree of uniformity in blending than has been obtainable heretofore by any of the methods known to the prior art.

The specific nature of the invention as well as other objects and advantages thereof will clearly appear from a description of a preferred embodiment as shown in the accompanying drawings in which:

Fig. 1 is a vertical section through the blending apparatus is described.

Fig. 2 shows an alternate arrangement for the recirculating system.

This invention consists essentially of a method of and an apparatus for mixing powder grains by means of the circulation of an electrolytic mixing medium of lower specific gravity than the powder through a vat containing the powder grains, at a sufficient velocity to displace them with respect to each other, the preferred medium for this application being water which has been saturated with nitro-glycerine to prevent any of the nitro-glycerine content of the powder from being absorbed by the water. The powder grains to be mixed are placed in a vat, the liquid mixing medium is added until it rises considerably above the top of the grains and then a jet of the liquid is ejected upwardly through the bottom of the vat at sufficiently high velocity to break through the surface of the liquid and fan out in a fountain-like manner. The grains located in the path of the jet are carried upwardly and outwardly along with the jet dropping back in a haphazard manner, thus being very thoroughly dispersed or mixed.

The apparatus consists of a base 1 on which is mounted a vat 3 in the form of an ellipsoid generated by revolution of an ellipse about its conjugate axis, the axis being disposed vertically. The vat 3 contains water saturated with nitro-glycerine. A charging door 5 is provided in the upper part of the vat 3 and a discharging door

7 near the bottom. A recirculating system is provided, the system consisting of an outlet pipe 10, a pump 11 and an inlet pipe 12 terminating in a nozzle 13 adjacent the bottom of and in the vertical axis of the vat through which a water jet 16 is forced by the pump 11. Outlet pipe 10 is covered by a baffle 14 and a screen 15 which prevents powder grains 24 from gathering around or passing into the outlet line 10 of the recirculating system.

The ellipsoidal form of vat is especially advantageous for this application since the tendency therein of the grains to slide toward the center without excessive crowding is uniform in all directions; however, any form of vat having a declivitous floor sloping toward a low point at which the nozzle can be located may be used.

A drain pipe 17 with a valve 18 is provided for draining water from the vat 3 into a storage reservoir (not shown). A screen 19 covers drain pipe 17 to prevent egress of powder grains 24.

For some applications it may be desirable to make use of gravity feed of the water, thereby maintaining a constant head and as a result, constant pressure at the nozzle 13 and uniform fountain effect in the vat. This construction is illustrated schematically in Fig. 2 in which a standpipe 30 would provide the necessary head. A feed line 31 leads from standpipe 30 to nozzle 13 with a valve 32 inserted to control the flow. An overflow line 33 and a drain line 34 with a shutoff 35, lead from vat 3 to a storage tank 36. Standpipe 30 is also provided with an overflow line 37 leading to storage tank 36. A pump 38 supplies water to standpipe 30 through a feed line 39.

In operation, a lot of powder, consisting of a predetermined quantity of powder from each of the batches to be blended is placed in the vat and sufficient water, saturated with nitro-glycerine, is added to fill the vat to a point well above the top of the powder grains and the outlet 10. Charging door 5 is then closed and pump 11 started, forcing a jet of water from the nozzle 13 to rise vertically upward from the bottom of the vat breaking through the surface of the water and fanning out in a fountain-like manner before falling back. As the grains in the middle of the vat 3, i. e., in the path of the jet 16, are carried upward and spread out on top, the mass settles toward the center so that eventually all grains are recirculated or redistributed, hence a high degree of dispersion is attained with a consequent uniformity of blend. By using an electrolytic liquid such as water as a circulating medium, the dangers resulting from static charges developed in blending towers are avoided and by saturating this water with nitro-glycerine, the nitro-glycerine content of the powder grains is maintained undiminished.

In the manufacture of service smokeless powder, particularly single-base service smokeless powder, the drying operation may be carried out by circulating warm water rather than air through the powder grains. It may be desirable to continue the drying process for the removal of volatiles in the nitro-cellulose powder, utilizing the blending process of this invention, thus combining steps in manufacture. However, notwithstanding this possible combination of operations, the superior blending obtained by this process would warrant the substitution of this step in manufacture for the conventional blending process as carried out in towers, particularly in view of the fact that blending towers now utilized are 75

inadequate for blending powder grains of a size necessary for some rocket propellant applications. A heating coil as indicated at 21 could be used to warm the mixing medium when desired.

5 While the preferred embodiment as above described is especially adapted for this application, modifications such as would occur to anyone skilled in the art may be made without departing from the spirit of the invention.

10 It is apparent from the description and drawings that this invention provides a method and apparatus whereby very large size grains of smokeless powder can be safely and thoroughly mixed, resulting in an improved blending of 15 various batches of powder into a final uniform index or lot.

I claim:

1. A method of blending powder grains including the steps of placing the powder grains to be 20 blended in a vat, adding a liquid of lower specific gravity than the powder grains in quantity sufficient to rise to a substantial height above the grains, said liquid being substantially a non-solvent with respect to said grains, and circulating

25 said liquid, including projecting a jet of the liquid upwardly from the bottom of the vat among the grains whereby the grains in the path of the jet are propelled upwardly into changed relation with respect to the other grains in the 30 vat.

2. A method of blending smokeless powder grains including the steps of placing the powder grains to be blended in a vat, adding water saturated with nitroglycerine, said water being added 35 in quantity sufficient to rise to a substantial height above the grains, and circulating said water by withdrawing it from the vat and projecting it upwardly through the bottom of the vat with sufficient velocity to break through the

40 surface and fan out in a fountain-like manner, whereby the grains in the path of the jet are propelled upwardly above the surface of the liquid to fall back in a haphazard manner on top of the other grains therein.

45 3. A method of mixing and drying particles of solid material containing a volatile constituent, including the steps of placing the solid particles in a vat, adding enough liquid of lower specific gravity than the solid particles in quantity sufficient to rise to a substantial height above the solid particles, said liquid being substantially a non-solvent with respect to the particles, maintaining said liquid at a temperature capable of volatilizing the volatile constituents thereof and

50 projecting a jet of the liquid upwardly from the bottom of the vat among the particles whereby the particles in the path of said jet are moved into changed relation with respect to the other particles in the vat.

60 4. The method of blending propellant powder grains which comprises placing in a vat the said propellant powder grains and a liquid of lower specific gravity than the powder grains, said liquid being substantially a non-solvent for the

65 constituents of the powder grains and present in sufficient quantity to rise above said grains; and circulating said liquid by withdrawing a portion thereof from the vat and injecting said portion in the form of a high velocity stream vertically upwards through powder grains and liquid in said vat, the velocity of said stream being sufficient to thoroughly mix the said grains.

CLARENCE N. HICKMAN.
